John J. Hickey INVENTOR
BY G. H. Beeler ATTORNEY

UNITED STATES PATENT OFFICE.

JOHN J. HICKEY, OF NEW YORK, N. Y.

DRIP PAN.

Application filed June 23, 1922. Serial No. 570,407.

To all whom it may concern:

Be it known that I, JOHN J. HICKEY, a citizen of the United States, residing at the city of New York, borough of Manhattan, in the county of New York and State of New York, have invented certain new and useful Improvements in Drip Pans, of which the following is a specification.

This invention relates to sanitary appliances and has particular reference to water safes or drip pans for use in connection with the drip water from ice boxes or refrigerators in dwelling houses, apartments, or other analogous places.

Among the objects of the invention is to provide a drip pan having peculiar adaptability for being kept clean and sanitary as well as to prevent any possibility of overflow or leakage of drip water upon the floor.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical section indicating diagrammatically one adaptation of my improvement to a refrigerator.

Fig. 2 is a plan view of a pan showing a cover, a portion of which is broken away.

Fig. 3 is a vertical section on the broken line 3—3 of Fig. 2.

Fig. 4 is a vertical transverse sectional detail on the line 4—4 of Fig. 3, showing especially the flush inlet and its relation to the discharge outlet from the pan.

Figs. 5 and 6 are sectional details of modified forms of couplings or unions which may be employed between the pan and the stand or waste pipe extending downward through the building.

Referring now more specifically to the drawings, the waste pipe 10 is extended downward through the floor 11 and along a wall 12 adjacent to which is located a refrigerator 13 having a drip pipe 14.

The pan comprises or includes a flat dish like body 15 whose bottom 16 is inclined rearward toward the discharge outlet 17

the axis of which is substantially horizontal and through the deeper side of the pan. The pan is bounded by an upwardly projecting flange 18 of any suitable design or finish and adapted to have expanse enough to receive the drip from any ordinary ice box or refrigerator if the pan is left with its top open.

The discharge outlet 17 comprises a nipple preferably threaded internally with a left hand thread 17' for the attachment of a coupling having right and left threaded ends for use in places where the pan is attached too close to the floor for it to be turned. The nipple is provided also with an external thread 17" for an outside union such as 70 suggested in Fig. 1 or as in Figs. 5 and 6.

Any suitable guard means may be formed over or provided for the discharge outlet 17. For this purpose I indicate a sort of grill including vertical bars 19 and a transverse bar 20 forming vertical slots 21 and an overflow slot 22 at the top.

As indicated I may provide for the pan a closure or lid 23 approximately of disk form and having a threaded periphery cooperating with an internal thread 24 formed on the rim 18, the lid being turned into or out of place by the application of a tool to the central boss 25 of angular form. This lid is imperforate or solid except for a 85 threaded boss 26 into which the drip pipe 14 may be tapped and also it is provided with one or more tapped bosses 27 into which I sometimes connect hot and cold water pipes from the house for flushing purposes. These 90 flush openings are shown however plugged at 28 because I prefer to employ a flush inlet such as shown at 29 formed approximately tangentially of the bottom of the pan and directed toward the discharge outlet or the grill portion thereof.

From time to time the sediment or any accumulation of filth within the pan may be dislodged and discharged positively by introducing a jet of water through the flush port 29 from 100 any water pipe in the building, the flushing water dashing directly against the grill and because of the tangential arrangement will swirl around the entire inner surface of the pan, thereby serving to thoroughly dislodge 105 and cleanse the interior of the pan whence the material will all be discharged into the waste pipe 10.

The back of the pan may be provided with one or more ears 30 through which a screw may be passed into the wall to additionally strengthen or stiffen the connection between it and the other parts.

In some instances, as in the case of unusually large pans, it is advisable to provide a support for the front portion of the pan, although in the usual practice the entire weight of the pan may be borne by the nipple 17. To this end I show a leg 31 threaded for vertical adjustment in a boss 32 formed or cast on the bottom of the pan. The angular head portion of the leg is adapted to rest on the floor and through which the leg may be adjusted up or down. I would point out also that the interior of the nipple 17 is recessed at 17^a forming a shoulder against which the end of the connecting pipe co-operating with the thread 17' may abut, making a tight joint and with the bottom of the pipe opening on about the same level as the adjacent bottom portion of the pan.

I claim:

1. The herein described dish like drip pan for refrigerators having an inlet for drip water and a discharge outlet extending laterally from one side and adjacent to the bottom of the pan, grill means within the pan guarding said lateral outlet, and means separate from the inlet and directed horizontally and tangentially across the inside bottom portion of the pan directly against the grill for admitting a flushing fluid for dislodging accumulations of sediment from the grill.

2. A drip pan as set forth in claim 1 including a lid independent of the flushing means.

3. The herein described dish like drip pan having an inlet for drip water and a discharge outlet, and means separate from said inlet for admitting thereto a flushing fluid for dislodging and cleansing therefrom any accumulations of sediment, the pan having an upwardly projecting circular flange internally screw threaded, and a lid detachably screw threaded within said flange.

4. In a drip pan for refrigerators, a main body of substantially circular form in plan and having a lateral discharge outlet at its bottom, a substantially water tight lid removably secured to the body, said lid being provided with means for attaching a vertical drip pipe from the refrigerator thereto, and means to admit a flushing fluid across the inside of the bottom of the pan independent of the drip connection.

5. In a drip pan for refrigerators, a main body of substantially circular form in plan and having a lateral discharge outlet at its bottom, a substantially water tight lid removably secured to the body, said lid being provided with means for attaching a vertical drip pipe from the refrigerator thereto, and means below the lid for admitting into the interior of the pan a flushing fluid substantially at right angles to the axis of the discharge outlet for causing a swirling of the flushing fluid within the pan.

In testimony whereof I affix my signature.

JOHN J. HICKEY.
